EXPLOSION-MOTOR.

1,089,462.

Specification of Letters Patent. Patented Mar. 10, 1914.

Application filed April 20, 1910. Serial No. 556,462.

To all whom it may concern:

Be it known that I, MARK B. CRIST, a citizen of the United States, and a resident of Pittsburgh, in the county of Allegheny and 5 State of Pennsylvania, have made a new and useful Invention in Explosion-Motors, of which the following is a specification.

This invention relates to the general class of explosion motors but particularly to that 10 class in which the explosion charge consists of a mixture of air and gas.

It is well known that gases having different B. T. U. values require different proportions of air to effect proper combustion 15 in the explosion chamber of the motor. For example the proportion of producer gas to air is generally about 1 to 1 while the proportions of natural gas to air is about 1 to 13. The proportioning of air and gas for the 20 combustion fuel may be provided by arranging different port cuttings in a piston admission valve whose ports communicate with the air and gas inlets and the proper proportions will be maintained so long as the 25 value of the gas remains constant. If however, as might easily be the case where producer gas is used, and the mixture is adjusted for the most economical operation the B. T. U. value of the gas falls off, the relative 30 proportions of air and gas entering the combustion chamber will be such as not to produce the proper mixture because as the gas becomes poorer the percentage of air to gas should be decreased and as the gas becomes richer again the relative proportion 35 of air to gas should be increased. It becomes desirable then to provide means whereby a proper mixture will be maintained irrespective of variations in the B. 40 T. U. value of the gas. If however the engine is operating on gas of constant B. T. U. value, the richness of the mixture will be varied in proportion to the load.

I have provided means for maintaining 45 the admission fuel mixture in proper proportions of air and gas irrespective of variations in the quality of the gas during the operation of the engine so that should the gas decrease in quality, a greater proportion 50 of gas may be admitted as part of the mixture than would be admitted when the gas was rich. Instead of throttling the gas, the air may be throttled, or if desired, the air and gas could be throttled simultane-

ously; that is, more air admitted at the same 55 time that less gas was admitted or vice versa.

Such a means as just described is adapted to be used in the main line for a bank of engines running in parallel. It becomes desirable in actual engine practice to govern the charge locally; that is, for each individual engine due to change in load, and I have provided means for accomplishing this result, one form of which is illustrated in 60 the accompanying drawings in which the figure is a cross sectional view through a gas engine cylinder equipped with a mixing valve.

The figure is a cross sectional view 70 through a gas engine cylinder equipped with a mixing valve constructed in accordance with my invention, and a throttling regulator shown in vertical section and partly in elevation.

By referring to the drawings by numerals of reference, 1 designates a gas engine cylinder provided with the usual exhaust valve 2. The cylinder is shown as being provided with an inlet port 3 having a mixing valve 4 comprising a casing 4 provided with gas ports 5 and air ports 6. Within the casing 4 is a reciprocatory piston or trunk valve 7 having gas and air ports designated by the reference numerals 5^a and 6^a and adapted 80 to register with the gas and air ports in the casing 4. The valve 7 is carried by the stem 8 of a mushroom valve 9 which normally closes port 3 but the movement of which is synchronous with that of the valve 7. The 90 valve stem 8 carries a head or disk 10 which is spring pressed so as to normally keep the valve 9 closed and consequently the valve 7 closed. The valves 7 and 9 are intermittently moved in opening directions by a 95 rocking lever 11 shown as fulcrumed at 12 and actuated by rod 13 from some suitable shaft in a well known manner. On the shaft 8 is shown an arm 14 adapted to be connected to a governor or speed responsive 100 device whereby a change in load will rotate the valve 7 about the valve stem 8 and throttle the charge. When the lever 11 is caused to effect an inward movement of the valves 7 and 9 the ports 5 and 6 are opened 105 and the proper quantity of air and gas will be admitted to the combustion chamber. If the load remains constant, a given quantity

of gas and air will pass through the ports 5 and 6 and the port cuttings 5^a and 6^a in the valve 7. If the load increases, however, it may be necessary to admit a richer mixture, that is, change the proportion of air and gas so as to admit more gas in proportion to the amount of air. If the load falls off, a lean mixture may be employed, that is, less gas and relatively more air. I have provided means for taking care of changes in load so as to vary the amount of air and gas passing into the mixing valve 7.

By reference to the drawings it will be observed that 15 designates a butterfly valve in the gas supply pipe 16. The link 17 connected to said valve 15 is also connected to a link 18 which in turn is connected to a lever 19 fulcrumed at 20 on a bracket 21 on the stationary element 22 of a pressure regulator illustrated as a gasometer. The stationary element or tank 22 of the pressure regulator is in communication with the pipe 16 through a pipe 23 so that the pressure within the movable element or bell 24 of the gasometer will be dependent upon the pressure in the pipe 16. The movable member or bell 24 of the gasometer is connected to the lever 19 by link 25 so that any movement of the lever 19 which will impart movement to the link 18 will likewise impart movement to the link 25 and therefore move the bell 24.

An adjustable controlling means is provided for actuating the bell illustrated as a spring 26 connected to the lever 19 on the side of the fulcrum 20 opposite to that on which the links 18 and 25 are. The spring 26 is connected to a threaded pin 27 passing through an internally threaded adjusting wheel 28 carried on the pin 27 and which secures it to the lever 19. The other end of the spring 26 is connected to one end of a lever 29 which may be removably fulcrumed to the bracket 30 or 31 on the post G. The brackets 30 and 31 have fulcrum receiving openings 32 and 33 respectively so that the lever 29 may be caused to be fulcrumed to either bracket to suit existing conditions. The lever 29 is connected to a collar 34 of the speed responsive device 35 which is illustrated as a centrifugal governor.

Under ordinary conditions the valves 7 and 9 will receive constant intermittent movement through the lever 11, the link 13 and a cam which actuates it. If the load increases on the engine the governor balls will have a tendency to move inward. If the lever 29 is fulcrumed at 32 tension will be put on the spring 26, having a tendency to depress the gasometer dome 24 and open the valve 15 so as to increase the flow of gas through pipe 16 and through the opening 5 and port cutting 5^a. If the load falls off the governor balls will fly out, the lever 29 will be depressed at the spring end, the spring

will be put under compression, the gasometer dome 24 will be raised, the valve 15 will be partially closed, and the gas flow will be retarded. Under some conditions, however, it may be desirable to have just the opposite operation take place under the same conditions. For example, it may be desirable to decrease the pressure in the pipe 16 under heavy loads and to increase it under light loads and for this condition the lever 29 may be fulcrumed at 33 instead of 32. In order to make a standard device I may arrange on the post G both arms 30 and 31 so that the device will be adapted to be used under either of the two conditions.

From the foregoing it will be seen that I have provided an efficient means for locally controlling the various mixtures according to the variation in load and that the regulator will respond quickly to changes in position of the collar 34 of the speed responsive device 35.

From the foregoing it will be apparent that if there is a given pressure in the gasometer and the governor weights move in, and assuming that the lever 29 is fulcrumed at 32, the bell 24 will be depressed so as to increase the pressure in 24 and cause more gas to be admitted to the combustion chamber of the engine. If the engine speeds up too much the governor weights will move out relieving pressure in the bell 24 and less gas will pass into the engine. It will be apparent that the gasometer is controlled by the governor so that there will be variations of pressure and therefore variations of rate of flow according to the speed of the engine resulting in variations in the quality of the gas.

Having now described my invention, what I claim is:

1. In a gas engine, the combination with a mixture governing valve, air and gas conduits leading to said valve, a valve in one of said conduits and independent of the first named valve, a pressure regulator connected to the last named valve, and a speed responsive device connected to the pressure regulator.

2. In a gas engine, a mixture governing air and gas conduits leading to said valve, pressure regulated means for varying the pressure in one of said conduits, and a speed responsive device for controlling the pressure regulated means.

3. In an internal combustion engine, a valve, conduits leading to said valve, a pressure regulator in communication with one of said conduits, and a speed responsive device for controlling the pressure regulator, a valve in one of said conduits, and means connecting the last named valve to said pressure regulator and to the speed responsive device.

4. In an internal combustion engine, a

- mixture governing valve, air and gas conduits in communication with said valve, a valve in one of said conduits, a pressure regulator in communication with one of said conduits, a speed responsive device for controlling the pressure in said pressure regulator, and means for connecting said pressure regulator to the last named valve.
5. In a gas engine, a mixture governing valve, air and gas conduits leading to said valve, a speed responsive device, and means responsive to variations in position of a movable part of said speed responsive device for varying the pressure in one of said conduits.
- 10
- 15
6. In an internal combustion engine, a mixture governing valve, air and gas conduits in communication with said valve, a pressure regulator in one of said conduits, a speed responsive device on the engine and controlling said regulator to vary the rate of flow through one of said conduits. ²⁰

In testimony whereof, I have hereunto subscribed my name this 18th day of April, 1910.

Correction in Letters Patent No. 1,089,462.

It is hereby certified that in Letters Patent No. 1,089,462, granted March 10, 1914, upon the application of Mark B. Crist, of Pittsburgh, Pennsylvania, for an improvement in "Explosion-Motors" an error appears in the printed specification requiring correction as follows: Page 2, line 115, after the word "governing" insert the word *valve*; and that the said Letters Patent should be read with this correction therein that the same may conform to the record of the case in the Patent Office.

Signed and sealed this 31st day of March, A. D., 1914.
